Machine Company, Chicago, Ill., a corpora-
tion of Illinois

Application May 3, 1940, Serial No. 333,128

18 Claims. (Cl. 93—2)

The machine of the present invention is designed for use in sealing the ends of wrappers in the closing of packages containing articles of merchandise; and the invention in particular relates to the means provided for adjusting the sealing crimpers toward or from one another to accommodate packages of varying lengths in conjunction with the means provided for vertically adjusting the entire mechanical assembly with respect to the feeding plane of the packages, so that the sealing crimps may be applied at each end of the package along lines applied either medially of the package or above or below the medial plane. This adjustment is desirable in order to accommodate the machine to packages of varying configuration, which often requires that the sealing crimp be applied either along or near the base of the package or at varying elevations with respect thereto in order to accommodate articles or units of merchandise of irregular shape and contour.

The invention is further directed to the means provided for advancing the packages in the form of a procession to the sealing line and to the synchronizing of the operations of the crimping mechanism to the speed of delivery of an associated gluing and sheeting machine, so that a procession of sheets will be delivered at the required intervals to permit the operator to wrap the sheet around an article of merchandise and place the same in position to be fed forwardly to the crimpers in timed relation to the delivery of the sheets, thereby maintaining continuity in the folding, sealing and delivering of the packages.

The invention also relates to the construction and mode of operation of the crimpers; to the feeding mechanism for the packages; to the means provided for slitting the crimped ends of the packages during the sealing operation to facilitate tearing away of the wrapper, and to the general construction of the machine as a whole and the constituent parts thereof.

Further objects and details will appear from the description of the invention in conjunction with the accompanying drawings, wherein—

Figure 1 is a plan view of the machine associated with a gluing and sheeting machine to facilitate the application of the wrappers;

Fig. 2 is a side elevation of the combined mechanism;

Fig. 9 is an enlarged sectional view taken through line 9—9 of Fig. 6 showing the mounting for the upper shear blade;

Fig. 10 is a detail of the toggle mechanism for actuating the jaws;

Fig. 11 is a perspective view of the feeder and associated parts;

Fig. 12 is a detail showing a modification particularly adapting the device for the feeding of packages in pairs;

Fig. 13 is a cross sectional elevation illustrating the adjusting principles of the present invention as applied to a machine employing crimping rollers and a chain feed in lieu of the jaw crimpers illustrated in the previous views; and

Fig. 14 is a longitudinal sectional elevation taken on line 14—14 of Fig. 13.

30 The crimping mechanism of the present invention in the form illustrated in Figures 1 to 11, inclusive, is shown in association with a gluing and sheeting machine 20 of the character fully set forth and described in my copending application, Serial No. 315,561, filed January 25, 1940.

It is not deemed necessary to describe this machine in full detail save insofar as may be necessary to an understanding of its cooperative relationship to the crimping machine of the present invention.

The sheeting machine is built upon a framework comprising corner legs 21 and a top frame 22 which carries a table 23 which is projected outwardly beyond the frame of the gluing and sheeting machine and affords the frame or support for the crimping mechanism, which is thus associated and combined with the gluing and sheeting unit in the form of an extension thereto.

45 The gluing and sheeting machine operates to intermittently feed forward from a roll 24 a continuous web W, which may be of paper, fabric, or a transparent sheet of cellulose of the kind commonly employed at the present time in the wrapping of bread loaves and other bakery prod-

ucts, articles of apparel, and other units of merchandise too numerous to mention.

The web W is fed forward upwardly, thence rearwardly, and finally forwardly through rollers 25, and has glue stripes or lines applied to its margin by gluing mechanism 26, and in addition is provided at recurrent intervals with cross glue lines applied by means of a cross traveling gluing carriage 27 which is shuttled back and forth by cable mechanism 28 in a manner described in full detail in my copending application referred to.

The continuous web W is advanced by a feed roller 29 which is intermittently rotated by a rack and ratchet mechanism 30, and the forward end of the web is cut off recurrently by shear mechanism 31 into sections of uniform size which as shown are glued along each of the four edges, as illustrated in the case of the section S shown in Fig. 1.

All of the mechanisms of the present invention are driven from a common source of power, which may be a motor 32 which actuates the main drive pulley 33, which in turn drives a gear 34 mounted upon a shaft 35 having oppositely extending cranks 36 and 37. The crank 37, through a link 38, oscillates an arm 39 depending from a shaft 40 which carries an oscillating arm 41 to which the rack 30 is pivoted, and also carries an arm 42 which is connected with and actuates the cable 28 for shuttling the transverse gluing mechanism back and forth across the under side of the web.

Suitable means are provided for regulating the extent of each feeding stroke imparted by the rack 30 and for regulating the length of the glue lines, so that sheets of the intended length and glued in the intended manner will be intermittently cut off in properly timed relationship and delivered on to an endless carrier 43 presenting its upper turns across the top of the table 23 and in a convenient position to enable the operator to remove the sheets at regularly timed intervals for the purpose of wrapping the same around the articles of merchandise to be enclosed and sealed.

All of the above mechanisms are fully described in the copending application, Serial No. 315,561, and it is therefore not deemed necessary to further describe the same except to point out that the association of the sealing mechanism with the sheeting and gluing mechanisms enables both of these units to be synchronously driven from a single source of power, so that sheet sections of uniform size, freshly glued, will be delivered at suitably timed intervals, which enables the operator to wrap them around the units of merchandise to bring the longitudinal edges in overlapping relation as indicated in dotted lines in Fig. 2, and to thereupon place the longitudinally sealed package in position to be carried forward to the crimpers, so that the sheet delivery and wrapping will keep proper pace with the feeding of the partially sealed packages to the crimpers which tuck in and seal the ends of the wrappers and deliver the fully sealed packages in regular sequence at the discharge end of the machine.

The crimping mechanism which displays the special features of the present invention is fully supported by the projecting end of the table 23 which is provided with a transversely elongated rectangular opening 44, which across its center is bridged by a series of spaced guide bars 45 which furnish a grid across which the packages are moved. Below the longitudinal center of the table extension is located a guide rod 46 which

is suspended at its ends by outer and inner brackets 47 and 48 respectively, which hold the guide rod rigidly in position at a substantial distance below the table, as illustrated in Fig. 2. The guide rod 46 serves as a mounting for a rider 49 provided with forward and rear lugs 50 and 51, which embrace the guide rod and permit the rider to be moved back and forth thereon.

In order to apply the moderate amount of friction required in the operations presently to be described, a friction block 52 is provided which bears against the surface of the rod and is carried by a plate 53 held in place by a spring backed screw 54 entered into the lug 51, which enables the degree of friction to be regulated.

The rider 49 near its forward end is provided with an upstanding post 55 which at its upper end carries an angled cross arm 56, giving to the structure a T-shaped formation, and the cross arm in turn supports a pusher bar 57 having lugs 58 which engage the rear side of a positioned package as in Fig. 1. The pusher bar is also provided with forwardly projecting tucker fingers 59 which are spaced to clear the body of the package enclosure and tuck in the ends of the wrapper preparatory to the sealing operation.

The tucker fingers 59 cooperate with fixed tucker fingers 60 adjustably mounted upon posts 61, so positioned as to engage the forward side of the package and tuck in the projecting ends of the wrapper in cooperation with the action of the fingers 59 when the package is advanced to the sealing position shown in Fig. 4, so that the ends of the wrapper will be properly tucked in on both sides before the sealing pressure is applied.

The pusher bar 57 is held in position by a thumb nut 62 which enables any pusher bar to be removed and another substituted in order to provide a bar of the proper size to act upon packages of a given dimension. The pusher bar occupies a position immediately above the plane of the table top, and in order to advance the preceding package after the sealing operation, a pusher arm 63 is provided which is of bell crank formation and terminates in an upstanding leg 64, being pivoted at the point 65 to the rider 49. The forward end 66 of the pusher arm is bent upwardly and affords support for a cross plate 67 carrying fingers 68, which when the pusher arm is elevated extend above the table top and in position to engage the rear face of the forward package and carry it forward as indicated in Fig. 5. It is therefore necessary for the active end of the pusher arm to drop downwardly below the level of the table to clear the underside of the package previously advanced by the pusher bar, and the linkage now to be described is provided to afford the required movements.

The rider 49 near its rear end is provided with a fin 69 upon which is pivoted a lever 70 connected at its upper end by a link 71 with the upstanding leg 64 of the pusher arm 63. The lower end of the lever 70 is connected by a spring 72 which extends forwardly and connects with a lug 73 carried by a slide 74 which rides upon the fixed guide rod 46 within the open space between the lugs 50 and 51 at the ends of the rider 49. The slide 74 is actuated by a link 75 (Fig. 2), the rear end of which is pivoted to a lever 76 mounted upon the shaft 40 (Fig. 2), and the lower end of the lever is engaged by a link 77 actuated by the crank 36.

The arrangement of these parts is such that when a forward thrust is imparted to the slide 74 it will first of all put tension upon the spring 72

and draw forward the lower end of the lever 70, the friction block 52 meanwhile acting as a brake to prevent the premature movement of the rider 49, which, however, will begin to move under the pull of the spring as the slide 74 continues to advance. The initiatory movement, however, imparts a pull through the link 71 to the rear leg 64 of the pusher arm, which elevates the forward or free end of the arm and brings the pusher arm finger 68 into position to engage the rear side of the foremost package occupying the sealing position. After the initiatory movement is exhausted the rider 49 as a whole will advance and the rear package will be engaged by the tucker fingers 59 and the lugs 58, and advanced to the sealing position concurrently with the advancement of the preceding package. On the return stroke of the link 75 and the slide 74, the spring 72 will be relieved from tension and the free end of the pusher arm will drop back below the level of the table so as to clear the package now occupying the sealing position.

The degree of movement imparted to the pusher arm can be regulated by stop screws 78 and 79, and the tension of the spring 72 in relation to the braking action of the friction block 52 is so regulated as to insure the lifting of the pusher arm before the rider begins to advance. The forward movement of the rider is limited by an adjustable stop 80 near the forward end of the rod 46 with a spring 81 to cushion the contact of the rider.

Sealing is effected by upper and lower jaws 82 and 83, which when open occupy the positions shown in Figs. 2, 3 and 4, and when closed occupy the positions shown in Figs. 5, 6 and 7; and each of the jaws is provided with a serrated face 84 and is chambered on its interior to receive a heating coil 85 (Fig. 7). The lower jaw 83 is supported on an asbestos insulating plate 83^a carried by a casting 86 having sleeves 87 which are slidable upon a pair of spaced vertical rods 88 which at their upper ends support a housing 89 which yieldingly carries the upper jaw 82 in the manner to be presently described.

The vertical rods 88 are slidably mounted within sleeves 90 which are formed along the forward and rear edges of a supporting frame casting 91 which is provided with upper and lower transversely extending sleeves 92 and 93 which ride upon upper and lower cross guide rods 94 and 95, the ends of which are reduced and supported within vertically adjustable blocks 96 which permit the entire sealing assembly to be vertically adjusted as a unit in the manner now to be described.

The entire sealing assembly is suspended from the table top on each side by a hanger yoke 97, which yokes are supported from channel bars 98 (Fig. 3) rigidly secured to the table extension, and constitute a part of the fixed framing of the machine. The lower ends of the hanger yokes are connected and spaced by a transverse bridge bar 99, which arrangement affords the necessary rigidity for supporting the sealing assembly and permitting the vertical and transverse adjustments which are provided for.

The blocks 96 are channeled vertically to afford side flanges 100 (Fig. 2) which embrace the sides of an adjustable supporting post 101 which is guided within upper and lower bushings 102 and 103. The post terminates in a head 104 which receives the threaded stem 105 of a hand wheel 106, and the adjusting motions so imparted to the post 101 are imparted to the associated block

96 through a trunnion pin 107, the projecting ends of which are entered through slots 108 in the spaced side flanges 100.

The above arrangement is duplicated on each side of the machine, and thus enables the blocks 96 to be individually adjusted, which is possible by reason of the fact that the blocks are mounted upon the pins, so that a certain amount of tilting movement is permissible.

Inequality of vertical adjustment may be desirable in the case of certain packages which are asymmetrically folded so that the sealing plane will differ at opposite ends of the package.

The frame castings 91 are adjustable in opposition to one another by the provision of a right and left screw 109 which is threaded through both of the frame castings and operated by a hand wheel 110 (Fig. 3). The adjusting screw 109, as shown in Fig. 4, occupies a position parallel to the lower guide rod 95 and on the forward side thereof.

The vertical rods 88 of each pair are connected at their lower ends by a cross head 111 (Fig. 5), and have their upper ends entered into the housing 89, which arrangement holds the rods in rigid parallel relation to one another and enables them to slide freely through the mounting afforded by the main frame casting 91, and each casting is provided on its outer face with aligned bosses 112, 113 (Fig. 4) which furnish guides for the reciprocation of a toggle actuating rod 114 provided near its opposite ends with cross pins 115, 116, which receive the contiguous bifurcated ends of two pairs of toggle links 117, which bifurcated ends are interfitted and pivoted upon the associated pin, as illustrated in Fig. 10. The lower ends of the lower toggle links are pivoted to upstanding lugs 118 at the ends of the bar 111, and the upper ends of the upper toggle links are similarly pivoted to the projecting ends 119 of a plate 120, which closes the side of the casting 86 which supports the lower crimpler jaw.

The rear end of each of the rods 114 is provided with a cushion spring 121 which is adapted to be contacted in any position of transverse adjustment by an angle shaped transversely extending thrust bar 122 carried by the slide 74, so that as the slide advances from the position shown in Fig. 4 to the position shown in Fig. 5, the rod 114 will be moved forwardly and the toggles spread to a position very slightly beyond dead center. This spreading of the toggles causes the lower jaw to move upwardly under the direct thrust of the upper toggle links, and causes the upper jaw to move downwardly under the down pull of the rods 88 which are subjected to the down thrust of the lower toggle links.

On the return movement of the slide 74, the links are retracted and folded by the pull of a chain 122^a carrying a link 122^b which journals a roller 122^c mounted upon a rail rod 122^d suspended at its ends from the transverse thrust bar 122, the rail permitting transverse adjustment of the chain commensurate with the transverse adjustment of the jaw assembly and the toggles forming a part thereof.

As shown in Figs. 6 and 7, the upper jaw is longitudinally supported at its ends from hanger pins 123 each provided with a collar 124 and a reduced upper end 125 entered through a bore in an adjusting nut 126 having a knurled head 127 and threaded into the upper end of an upstanding cored boss 128 which is provided with a shoulder 129 against which the collar 124 abuts, while the reduced end 125 is surrounded by a

coil spring 130, the tension of which may be regulated by the adjustment of the nut 128.

The stroke of the toggle links is sufficiently long to cause a slight continued upward movement of the two jaws after they are brought into sealing contact, at which point the jaws will move in unison, the upper jaw yielding against the tension of the springs 130. This added movement is availed of to trim the projecting sealed edges of the wrapper by the action of a shear blade 131 carried by the outer edge of the lower jaw in conjunction with an upper shear blade 132 carried by cross pins 133 entered through the rods 88, which do not partake of the terminal yielding movement imparted to the upper and lower jaws, so that during this movement the lower blade will shear past the descending blade 132 and evenly shear off the excess from the sealed ends of the wrapper.

The mounting for the shear blade 132 is illustrated in Fig. 9, from which it will be noted that the pins 133 are slidable through the rods 88 against the tension of springs 134 which bear against washers 135 on a cross bar 136 carried by the pins 133. The angularity of the shear blade 132 may be regulated by the adjustment of screws 137 and 138 bearing against the blade and acting against the tension of backing springs 139 located within recesses 140 in the bar 136, so that the blade may be regulated to secure an effective shearing action.

In addition to the shearing action, it is desirable to provide an oblique tearing slit T (Fig. 8) in the sealed edge of the wrapper to facilitate the opening of the package by initiating a tearing line converging inwardly of the wrapper, and for this purpose a serrated knife blade 141 is provided which is located within a slot 142 at one end of the upper jaw in position to permit the knife blade to enter a registering slot 143 in the lower jaw. The knife blade is carried by a hanger 144 secured at its upper end to the post 128, so that as the terminal movement is imparted to the upper and lower jaws in unison the knife blade, moving downwardly, will cut through the sealed edge of the wrapper to provide the end slit T.

In order to steady the package during the end sealing operation, a shoe 145 is suspended by rods 146 (Fig. 3) which are entered through a bracket 147 slidably mounted upon a bridge bar 148 supported at its ends from standards 149 on opposite sides of the machine. Each rod 146 is provided with a collar 150 which receives the thrust of a spring 151, the upper end of which bears against the bracket 147, nuts 152 being provided to regulate the tension of the springs.

In order to regulate the current flow through the heating coils 85 in the jaws, a thermostat 153 is provided, which is adjustable by a lever arm 154 located outside of the housing 89.

It may be desirable to provide for the simultaneous feeding and sealing of packages in pairs, and for this purpose the modification shown in Fig. 12 is employed. In this instance, in lieu of the pusher feed mechanism heretofore described, an endless chain 155 is employed which is provided with stop lugs 156 at spaced intervals, against which pairs of packages P are positioned, and the chain feed is advanced intermittently by any suitable train of connections to bring the packages to the sealing point. Also, in this form of construction, it is desirable to employ toggle link 157 of the form shown, each of which consists of a hollow section 158 and a telescoping link rod 159 entered through a cap nut 160, which

bears against a collar 161 backed by a coil spring 162 bearing against a shoulder 163 in the hollow link section 158. Normally the link sections will move in unison, but an excess terminal movement 5 may be accommodated by the yielding of the link rods 159. In all other essential respects the structure shown in Fig. 12 is substantially like that first described.

The adjusting features of the present invention, 10 including the vertical adjustment of the assembly as a whole combined with the lateral adjustments of the sealing members, are adapted for use in a sealing machine employing rollers rather than jaws for sealing purposes, and such an embodiment of the adjusting features is illustrated in Figs. 13 and 14. In this embodiment, the packages are fed forward upon intermittently moving feed chains 164, provided with prongs 165 which engage the packages which are moved over 15 a stationary grid 166 composed of longitudinally extending rods between which the prongs 165 project.

The end edges of the wrapper are compressed together by the contact of endless spring belts 25 167 bearing against the upper and lower faces of the wrapper margins, which spring belts are carried around upper and lower forward rollers 168 and rear rollers 169, the rear rollers being power driven.

30 The sealing of the edges is effected between upper and lower heated rolls 170, and the excess at the margins is trimmed away by rotary cutter blades 171. It will of course be understood that the spacing of the spring belt compressors and 35 the sealing and cutting knives is so regulated as to cause these elements to engage only the compressed end margins of the wrapper, leaving the space in the center free for the advance of the package, as indicated in Fig. 13.

40 The rollers 169 and the rolls 170 are power driven from a transverse shaft 172 which is grooved to mount a sprocket 173 which drives a sprocket chain 174 the rear turn of which is carried up and over suitable sprockets of the 45 lower roll 170 and roller 169, thence around an idler sprocket 175, and upwardly and around the upper roller 169 and roll 170, thereby causing these parts to rotate in unison with the feeding speed of the forward chains 164. The above 50 special features of construction are not herein claimed in detail, but the mounting for these parts is similar to that employed for adjusting the jaw crimpers first described.

55 It will be understood that the group of mechanisms illustrated in Fig. 14 is duplicated at opposite ends of the package, and in order to provide for the in and out transverse adjustments necessary to accommodate packages of varying lengths, each of the sealing groups is carried by a frame 60 176 provided with a hanger 177 through which is threaded a right and left adjusting screw 178 operated by a hand wheel 179 or crank, so that, by rotation of the screw, the sealing groups will 65 be moved inwardly or outwardly in opposition to one another to effect the necessary lateral adjustments within the adjustable frame 180, which supports the mechanisms previously described.

The vertical adjustments are effected by means 70 of a hand crank or wheel 181 operating a screw 182 entered through a lug 183, which constitutes part of the traveling frame 180, and the lower reduced end 184 of the screw is entered through a cap nut 185 in the upper end of a tubular fixed post 186 which affords the entire support for the

traveling frame and the sealing assembly carried thereby.

The traveling frame is provided with upper and lower collars 187 and 188 in widely spaced relation to one another, which embrace the post and permit a limited vertical movement to be imparted to the traveling frame 180. It is thus possible to vertically adjust the entire sealing assembly as a unit and to adjust the individual sealing groups laterally of the traveling frame. 10

Operation

In the operation of the mechanism first described, the power for operating the sheeting, feeding and sealing units is derived from a common source, and the movements are effected intermittently and in suitably timed relation to the wrapping of the packages performed by the operator, who occupies a convenient position between the sheeting and gluing mechanisms on the left side of the operator and the sealing mechanism on the right side. The cut and freshly glued sheets are delivered at properly timed intervals and are wrapped around the package, for instance a bread loaf, and sealed along the longitudinal overlap, and then placed transversely of the machine in position to be carried forward with the next reciprocation of the pusher feed mechanism, and as the pusher mechanism advances, the partially wrapped package will be engaged and the protruding ends of the wrapper tucked in on the rear side and the package carried forward to the sealing position, during which operation the forward sides of the wrapper ends will be tucked in while the jaws still stand in the open position shown in Fig. 4.

By the time the package has reached the sealing position, the cross thrust bar 122 will have been carried forward sufficiently to engage the toggle mechanism, so that the continued movement of the thrust bar will spread the toggles and move the jaws toward one another to engage and compress the protruding margins of the wrapper and bring them together at the sealing line.

In view of the fact that the packages during their advance are supported upon a fixed grid in the table top, and in view of the fact that the sealing assembly is vertically adjustable as a unit, it is possible to bring the jaws into sealing contact at any desired elevation with relation to the feeding plane of the package, so that the seal will be applied at the desired elevation above the base of the package, thereby accommodating the requirements for packages of irregular shape. For a symmetrical rectangular package like that shown in Fig. 8, the seal will ordinarily occur along the medial plane of the package, but for packages of irregular contour, some other plane may be found more favorable in order to produce a smooth, even and sightly seal, under more or less abnormal conditions.

The pusher feeding mechanism is so arranged as to carry forward the sealed package from the sealing position concurrently with the advance of a new package to the sealing position and to clear the forward package on its return movement so that a step by step advance of the procession of packages will be maintained to the discharging position. The arrangement shown is one which utilizes the thrust of the link 75 to time the various operations in proper sequence and irrespective of the lateral adjustment of the sealing jaws with respect to one another, since the thrust bar 122 is sufficiently extended to en-

gage the toggle mechanism in any of its positions of lateral adjustment.

The vertical adjusting mechanism employed with the jaw sealers is one which permits the ends of the frame carrying the sealing jaws to be adjusted uniformly, if desired, and also permits of a slight tilting of the frame, which may be desirable to accommodate packages of special shape, so that it is not necessary to seal both ends of a package along the same plane, since variation in this adjustment may be desirable. The mechanism as shown permits these adjustments to be effected without binding or cramping, since the ends of the frame are supported upon trunnions afforded by the pins 107 carried by the adjustable standards 101.

By supporting the sealing assembly from the extended table top of the gluing and sheeting machine, and by utilizing a common source of power for both groups of mechanisms, an accurate timing is maintained, and the mechanisms are brought into convenient arrangement to meet the needs of the operator, and at the same time the general structure is simplified and rendered more compact since the entire mechanism can be moved from place to place as a unit, and in convenient relation to meet the requirements of the operator and the delivery of merchandise to a suitable location for wrapping and sealing.

Although it is customary, in the fastening of wrappers which require close sealing, to apply the glue line to the longitudinal overlap of the wrapper edges, preliminary to the sealing of the ends, it will be understood that the longitudinal sealing may not be necessary in certain cases and that mere overlapping of the edges will suffice to sufficiently enclose the package to permit the ends to be sealed by the mechanism herein described, so that it is not the intention to limit the use of the machine to wrapper sections which are provided with both longitudinal and transverse glue stripes.

Furthermore, in certain cases, glue will not be relied upon at all to afford the sealing, since certain wrapping materials will fuse under heat so that the seal will be effected without the presence of glue. Such wrapping materials, however, may require the longitudinal glue stripe to seal the overlap, heat being relied upon to seal the ends of the wrapper.

Furthermore, although the complete machine herein described is designed to seal both ends of a package and to permit the necessary lateral adjustments to be made to properly space the sealing groups, it will be understood that the jaw sealing mechanism and the means provided for actuating the same, as well as the pusher mechanism for feeding packages thereto, are regarded as special subjects of invention, which may be used either as a pair of jaw sealing groups or as a single group, so that in the claims, unless otherwise indicated, it is to be understood that the jaw sealing groups need not necessarily be employed in pairs as described.

65 We claim:

1. In a package sealing machine, the combination of two groups of sealing devices adapted each to seal the protruding ends of a package wrapper, means for laterally adjusting the sealing groups with respect to one another to accommodate packages of varying length, and means for vertically adjusting the entire sealing assembly to vary the sealing plane with respect to the position of the package.

70 2. In a package sealing machine, the combina-

tion of two groups of sealing devices adapted each to seal the protruding end of a package wrapper, means for laterally adjusting the sealing groups with respect to one another to accommodate packages of varying length, and means for vertically adjusting the entire sealing assembly to vary the sealing plane with respect to the position of the package, supporting means for the packages for maintaining the same in a fixed plane irrespective of vertical adjustments of the sealing assembly, and means for feeding packages forwardly to bring the protruding ends of the wrappers into proper relation to the respective sealing groups.

3. In a package sealing machine, the combination of two groups of sealing devices adapted each to seal the protruding end of a package wrapper, means for laterally adjusting the sealing groups with respect to one another to accommodate packages of varying length, and means for vertically adjusting the entire sealing assembly to vary the sealing plane with respect to the position of the package, supporting means for the packages for maintaining the same in a fixed plane irrespective of vertical adjustments of the sealing assembly, and intermittently operated reciprocating pusher mechanism provided with forward and rear pusher abutments adapted on each forward movement to advance a forward and rear package, and the forward abutment being adapted to clear the previously advanced rear package upon the return movement of the pusher mechanism.

4. In a package sealing machine, the combination of two groups of sealing devices adapted each to seal the protruding end of a package wrapper, means for laterally adjusting the sealing groups with respect to one another to accommodate packages of varying length, and means for vertically adjusting the entire sealing assembly to vary the sealing plane with respect to the position of the package, supporting means for the packages for maintaining the same in a fixed plane irrespective of vertical adjustments of the sealing assembly, and intermittently operated reciprocating pusher mechanism provided with forward and rear pusher abutments adapted on each forward movement to advance a forward and rear package, and the forward abutment being adapted to clear the previously advanced rear package upon the return movement of the pusher mechanism, the pusher mechanism being provided with a member adapted to engage and actuate the two sealing groups in all positions of lateral and vertical adjustment.

5. In a package sealing machine, the combination of means for advancing wrapped packages to the sealing position, two groups of sealing mechanisms adapted each to seal the protruding end of a package wrapper, adjusting mechanism for laterally adjusting the sealing mechanisms toward and from one another, said means including guide rails for the sealing groups and a right and left screw for simultaneously engaging both of the sealing groups to effect simultaneous adjustment thereof, and actuating means for both groups of sealing mechanisms adapted to actuate the same in all positions of lateral adjustment.

6. In a package sealing machine, the combination of means for advancing wrapped packages to the sealing position, two groups of sealing mechanisms adapted each to seal the protruding end of a package wrapper, adjusting mechanism for laterally adjusting the sealing mechanisms toward and from one another, and actuating means

for both groups of sealing mechanisms adapted to actuate the same in all positions of lateral adjustment, and means for vertically adjusting the sealing assemblage to vary the sealing plane with respect to the packages.

5 7. In a package sealing machine, the combination of means for advancing wrapped packages to the sealing position, two groups of sealing mechanisms adapted each to seal the protruding end of a package wrapper, adjusting mechanism for laterally adjusting the sealing mechanisms toward and from one another, said means including guide rails for the sealing groups and a right and left screw for simultaneously engaging both of the sealing groups to effect simultaneous adjustment thereof, and actuating means for both groups of sealing mechanisms adapted to actuate the same in all positions of lateral adjustment, and means for vertically adjusting the sealing assemblage to vary the sealing plane with respect to the packages.

10 8. In a package sealing machine, a sealing group comprising upper and lower sealing jaws and guide members for permitting a straight line reciprocation of the same to move from open to closed sealing position with respect to one another, toggle mechanism for actuating both jaws in unison and in opposition to one another, and a thrust bar for engaging and actuating said 15 toggle mechanism.

20 9. In a package sealing machine, a sealing group comprising upper and lower sealing jaws and guide members for permitting the same to move from open to closed sealing position with respect to one another, toggle mechanism for actuating the jaws in unison, pusher mechanism for advancing packages to sealing position, and toggle actuating mechanism movable with the 25 pusher mechanism and adapted to engage and spread the toggle mechanism to bring the jaws to closed sealing position after the arrival of a package.

30 10. In a package sealing machine, a sealing group comprising upper and lower sealing jaws and guide members for permitting the same to move from open to closed sealing position with respect to one another, toggle mechanism for actuating the jaws in unison, pusher mechanism for advancing packages to sealing position, said 35 mechanism including a rider carrying a rear abutment and a pivoted forwardly extending pusher arm having an upstanding forward abutment adapted to engage a package, a slide and connections for lifting the forward end of the 40 pusher arm at the beginning of the advance of the slide, and the slide thereafter actuating the rider to advance both the rear abutment and the forward abutment, and means carried by the 45 slide for engaging and actuating the toggle mechanism for closing the jaws.

50 11. In a package sealing machine, a sealing group comprising upper and lower sealing jaws and guide members for permitting the same to move from open to closed sealing position with respect to one another, toggle mechanism for actuating the jaws in unison, pusher mechanism for advancing packages to sealing position, said 55 mechanism including a rider carrying a rear abutment and a pivoted forwardly extending pusher arm having an upstanding forward abutment adapted to engage a package, a slide and connections for lifting the forward end of the pusher arm at the beginning of the advance of the slide, and the slide thereafter actuating the 60 rider to advance both the rear abutment and the forward abutment, and means carried by the slide for engaging and actuating the toggle mechanism for closing the jaws.

65 70 75

forward abutment, means carried by the slide for engaging and actuating the toggle mechanism for closing the jaws, and a flexible connection between the toggle mechanism and the slide for retracting and folding the toggle mechanism upon the return movement of the slide.

12. In a package sealing machine, the combination of a lower jaw and guide members upon which the lower jaw is slidably mounted, an upper jaw carried by said guide members, a rigid connection between the lower ends of said guide members, toggle links connected respectively to the lower jaw and to the lower rigid connection for the guide members, and means for recurrently advancing packages to sealing position, said means being adapted on the forward advance to engage and spread the toggle connections for moving the upper and lower jaws toward one another to sealing position.

13. In a package sealing machine, the combination of a lower jaw and guide members upon which the lower jaw is slidably mounted, an upper jaw carried by said guide members, a rigid connection between the lower ends of said guide members, toggle links connected respectively to the lower jaw and to the lower rigid connection for the guide members, means for recurrently advancing packages to sealing position, said means being adapted on the forward advance to engage and spread the toggle connections for moving the upper and lower jaws toward one another to sealing position, and a flexible connection between the toggles and the package advancing mechanism for retracting and folding the toggles upon the return movement of the advancing mechanism.

14. In a package sealing machine, the combination of a lower jaw and guide members upon which the lower jaw is slidably mounted, an upper jaw carried by said guide members, a rigid connection between the lower ends of said guide members, toggle links connected respectively to the lower jaw and to the lower rigid connection for the guide members, means for recurrently advancing packages to sealing position, said means being adapted on the forward advance to engage and spread the toggle connections for moving the upper and lower jaws toward one another to sealing position, a flexible connection between the toggles and the package advancing mechanism for retracting and folding the toggles upon the return movement of the package advancing mechanism, means for permitting lateral adjustment of the jaws and mountings therefor, and means for permitting lateral adjustment of the flexible connection to follow the lateral adjustment of the jaws and mountings.

15. In a sealing machine, the combination of upper and lower jaws and mountings therefor adapted to permit movement of the jaws toward

and from one another, the mounting for one of the jaws being yieldable under pressure, jaw actuating means for moving the jaws toward and from one another, said means having a range of movement sufficient to cause the jaws to move in unison in one direction after sealing contact is effected, and shear mechanism consisting of two blades one of which is movable with the jaws during said terminal movement in opposition to the other blade to effect a shearing action.

16. In a sealing machine, the combination of upper and lower jaws and mountings therefor adapted to permit movement of the jaws toward and from one another, the mounting for one of the jaws being yieldable under pressure, jaw actuating means for moving the jaws toward and from one another, said means having a range of movement sufficient to cause the jaws to move in unison in the same direction after sealing contact is effected, and a slitting knife blade and a mounting therefor adapted to hold the knife blade in position during the terminal movement of the jaws to slit through the wrapping material clamped between the jaws and provide a tearing slit.

17. In a sealing machine, the combination of upper and lower jaws and mountings therefor adapted to permit movement of the jaws toward and from one another, the mounting for one of the jaws being yieldable under pressure, jaw actuating means for moving the jaws toward and from one another, said means having a range of movement sufficient to cause the jaws to move in unison in one direction after sealing contact is effected, shear mechanism consisting of two blades one of which is movable with the jaws during said terminal movement in opposition to the other blade to effect a shearing action, and a slitting knife blade and a mounting therefor adapted to hold the knife blade in position during the terminal movement of the jaws to slit through the wrapping material clamped between the jaws and provide a tearing slit.

18. In a package sealing machine, the combination of means for advancing wrapped packages to the sealing position, two groups of sealing jaws adapted each to seal the protruding end of a package wrapper, adjusting mechanism for laterally adjusting the groups toward and from one another, two sets of actuating means, one for each group of sealing jaws, adapted to impart relative reciprocating movements to bring the jaws toward and from one another and laterally adjustable with the associated jaws, and a common operating member positioned to engage both sets of actuating means in all positions of lateral adjustment for operating the same.
